(57) **CLAIM**

(51) LOC (7) Cl. **14-02**

The ornamental design for a portion of a display panel or computer screen with an icon image, as shown and described.

(52) U.S. Cl. **D14/485**

(58) Field of Search D14/485-95; D18/24-33; D19/6; D20/11; D21/324-33; 345/326, 339-58

DESCRIPTION

(56) **References Cited**

FIG. 1 is a front view of a portion of a display panel or computer screen showing my new design; and, FIG. 2 is a front view of a second embodiment thereof. The broken line drawings of a computer screen in FIG. 1 and a display panel in FIG. 2, and words in both views, are for illustrative purposes only and form no part of the claimed design.
